INVENTOR.
Richard Klein
BY
Thomas J. Donnelly
ATTORNEY.

UNITED STATES PATENT OFFICE

RICHARD KLEIN, OF DETROIT, MICHIGAN

HAIR CURLING DEVICE

Application filed August 17, 1931. Serial No. 557,455.

My invention relates to a new and useful improvement in a hair curling device, and has for its object the provision of a simple and inexpensive device whereby the hair may be easily and quickly curled without the application of heat.

Another object of the invention is the provision of a device of this class which will be simple in structure, economical of manufacture, durable and highly efficient in use, and easily and quickly operated.

Another object of the invention is the provision of a device whereby the ends of the hair may be easily and quickly curled.

13 Other objects will appear hereinafter.

The invention consists in the combination and arrangement of parts hereinafter described and claimed.

The invention will be best understood by a reference to the accompanying drawings which form a part of this specification, and in which,

Fig. 1 is a perspective view of the invention.

23 Fig. 2 is a side elevational view of the invention, with a part shown in section illustrating the use of the invention.

Fig. 3 is a perspective view of a slightly modified form of the invention.

30 Fig. 4 is a perspective view of an assembly illustrating the modified use of the invention.

As shown in Fig. 1, the invention embodies a holding member which is formed from a single strip of resilient metal doubled upon itself to provide the pair of legs or members 9 and 10 which are substantially parallel to each other. The end of the member 9 is turned inwardly to serve as an abutment for one edge of the yieldable pad 12 which is mounted on the member 9. It will be noted that the member 9 is longer than the member 10 so that the angularly turned end 13 of the member 10 which is tapered at its edge as at 14 may be used to clamp hair 15 on the pad 12. This pad 12 is made from rubber or other suitable yieldable material. When the hair is clamped between the tapered edge 14 and the yieldable pad 12 and the device moved longitudinally of the hair, the hair will be crimped or curled as at 16. An operator by

clamping the hair between the engaging members and drawing the device longitudinally of the hair toward the ends thereof may easily and quickly effect a curling of the hair without requiring the necessity of heat and without endangering the person in any manner.

55 In Fig. 3 I have illustrated a comb element 17 mounted on the member 10 which will serve to separate the strands of hair as the device is drawn along the hair.

60 In Fig. 4 I have illustrated a slightly modified form of the device and also its use. I provide a pair of loops 18 each of which is provided with a retaining plate 20 on which a yieldable pad 19 is mounted. These loops 65 are intended to be secured on the index finger 21 and the thumb 22 so that the hair may be held by the pads 19 while the curling device is drawn longitudinally outwardly toward the ends. I provide a loop 23 having a retaining plate 24 on which a yieldable pad 25 is mounted. The loop 23 is designed to encircle the thumb 26 while the loop 27 is mounted on the index finger 28. A retaining plate 29 is carried by the loop 27 which serves to carry 70 the tapered presser plate 30. The operation of this construction is the same as is illustrated for the form shown in Fig. 1.

75 While I have illustrated and described the preferred forms of construction of my invention, I do not wish to limit myself to the precise details of structure shown, but desire to avail myself of such variations and modifications as may come within the scope of the appended claims.

80 Having thus described my invention, what I claim as new and desire to secure by Letters Patent is:

1. A hair curling device of the class described, comprising: a holding portion having a pair of separable parts; a yieldable pad carried by one of said parts; and a tapered engaging portion projecting outwardly from the end of the other of said parts and movable into engagement with said pad.

90 95 100 2. A hair curling device of the class described, comprising: a holding portion having a pair of separable parts; a yieldable pad carried by one of said parts; a tapered engaging portion projecting outwardly from the

end of the other of said parts and movable into engagement with said pad; and a combining member carried by one of said parts.

3. A hair curling device of the class described, comprising: a holding portion having a pair of separable parts; a yieldable pad mounted on the end of one of said parts; an angularly turned portion on the other of said parts and having a tapered edge engageable with said yieldable pad.

10 4. A device of the class described, comprising: a strip of resilient metal doubled upon itself to provide a pair of parallel extending members; a yieldable pad mounted on the inner surface of one of said members; an angularly turned end on the other of said members directed toward and movable into engagement with said pad.

15 5. A device of the class described, comprising: a strip of resilient metal doubled upon itself to provide a pair of parallel extending members; a yieldable pad mounted on the inner surface of one of said members; an angularly turned end on the other of said members directed toward and movable into engagement with said pad; and a combining member mounted on said pad bearing member.

20 6. A device of the class described, comprising: a strip of metal doubled upon itself to provide a pair of legs, one of said legs projecting beyond the end of the other; a yieldable pad carried on the inner face of the longer of said legs; and an angularly turned engaging portion on the shorter of said legs movable into engagement with said pad.

In testimony whereof I have signed the foregoing specification.

RICHARD KLEIN.
